Hanson & Hanson

UNITED STATES PATENT OFFICE.

CARL B. COOK, OF HADDONFIELD, NEW JERSEY.

CALENDAR.

1,310,905.

Specification of Letters Patent. Patented July 22, 1919.

Application filed March 9, 1916. Serial No. 83,072.

To all whom it may concern:

Be it known that I, CARL B. COOK, a citizen of the United States, and a resident of Haddonfield, Camden county, New Jersey, 5 have invented certain Improvements in Calendars, of which the following is a specification.

The object of my invention is to provide a calendar structure or calendar carrying 10 structure in which months or portions of months preceding and succeeding the current month may be readily displayed, with additional means whereby the days of the current week may be clearly distinguished 15 from the days of the preceding and succeeding weeks.

My invention may be embodied in a holder frame or casing to be employed as a desk calendar, or, with suitable modification 20 within the scope of my invention it may be employed as a wall calendar.

These and other features of my invention are more fully described hereinafter, reference being had to the accompanying drawings, in which:

Figure 1, is a perspective view showing my improved calendar structure in a form to be mounted upon a desk;

Fig. 2, is a vertical sectional view on the 30 line II—II, Fig. 1;

Fig. 3, is a similar view illustrating a modified detail within the scope of my invention;

Fig. 4 is a cross sectional view of a 35 slightly modified form of desk structure;

Fig. 5, illustrates a further modified detail of my invention, and

Fig. 6, is a perspective view of a portion 40 of a wall calendar structure embodying my invention.

In the drawings, 1 represents a suitable casing which may be substantially pyramidal in form, of the shape shown in Figs. 1, 2 and 3, or that shown in Fig. 4; such casing having a sight opening 2 through which the calendar dates are displayed. Within the casing are rollers 3 and 4 upon which an endless strip 5 may be wound; such strip carrying the calendar dates which 45 are displayed through the sight opening 2. The dates are displayed in continuous vertical lines in regular order, Sun., Mon., Tue., Wed., Thu., Fri., and Sat., while at the left hand margin of such strip the months may 50 be indicated. A card or backing 6 may be 55 employed to keep the calendar strip pressed forward, and this may be backed by a suitable brace as shown at 7.

The sight opening 2 of the casing 1 is of such a size as to exhibit the days covering 60 a period of one quarter of the year or thirteen weeks, and one object of my invention is to display at the center of such "sight" opening the current week; the days or dates of six weeks before and six weeks 65 after the current week being shown above and below the same.

A particular object of my invention is to clearly display or emphasize the days of the current week, and to this end various means 70 may be employed. In Figs. 1, 2 and 4, 6 represents transparent sheets of celluloid or the like which are of a shade or tone other than the shade or tone of the calendar sheet, preferably darker, and these sheets 75 stop above and below the current week disposed substantially at the center of the "sight" opening, so as to leave a clear space through which the latter is exposed.

In Fig. 3, I have shown the "sight" opening provided with a continuous sheet of transparent material 8^a, having shaded portions 8^b above and below the current week, and a plain central portion 8^c through 80 which the current week may be viewed.

In lieu of employing transparent material shaded so as to partially obscure the days or dates before and after the current week, I may leave the "sight" of the calendar frame or carrier structure entirely 85 open and place partitions in the form of substantially horizontal strips or bars 9, arranged above and below days or dates of the current week and, if desired, one of such strips may carry the names of the days 90 of the week above the respective dates. Such arrangement may be employed with a desk calendar structure, or with a wall calendar structure, as may be desired. In the use of my invention with a wall calendar structure, this can be readily arranged by mounting a calendar sheet or strip 5^a 95 upon a suitable card or other structural support 10 which will be cut or slotted as indicated at 10^a, 10^b, 10^c, so that the calendar sheet 5^a may be threaded in and out of the cuts; the latter cuts or slits being so disposed as to provide bars 9^a between which 100 the current week is positioned or displayed.

In the preferred form of construction 110

embodying my invention, the calendar sheet 5 is wound upon the rollers 3 and 4 within the casing 1, and may be worked back or forward as desired, and for this purpose 5 said rollers may be and preferably are provided with external handles 11 so that the calendar strip may be moved forward at weekly intervals, or as desired.

When the calendar structure with a continuous sheet is employed as a wall calendar, a single roller 3^a may be employed at the top of the sheet, card, or other support 10, or the bulk of the calendar sheet may be rolled up and placed in a suitable receptacle such as the housing 12, illustrated in Fig. 6. If desired, sections of the calendar strip representing single weeks may be torn off the bottom of the same as said strip is moved at regular intervals to bring successive weeks into view between the bars 9^a.

The casing is preferably made so that the back 13 may be opened to remove the old and insert fresh calendar strips, and for the purpose of holding the back in place a catch 14 may be employed, carried at the base of the casing. This catch may be of the usual snap character, the socket portion being mounted in a flap 15 which may be integral with the bottom 16. This bottom may also be movable; being hingedly connected to the face portion of the casing to facilitate the insertion and removal of the calendar strips.

While I have shown the dates arranged in substantially horizontal lines, with means 35 horizontally disposed for prominently displaying the current week, it will be understood that the arrangement of such days or dates may be changed, and that they may read in substantially vertical lines. It will 40 also be understood that my invention may be employed to bring into prominence any week line desired, or the current week of an ordinary month sheet, and that in some instances the emphasizing or week date line 45 exposing means may be movable with respect to a relatively fixed calendar sheet or strip.

I claim:

1. The combination with a calendar sheet having a multiplicity of date lines representing weekly and monthly divisions of

time, of a mounting for said calendar sheet arranged to display a definite number of said week date lines, and means whereby any single week date line of said number may be selectively indicated with greater 55 prominence to the exclusion of the others.

2. The combination with a calendar sheet having a multiplicity of date lines representing weekly divisions of time, of means for supporting the calendar sheet and displaying a plurality of said date lines, and means substantially centrally disposed for prominently displaying the current week date line independently of the preceding and succeeding week date lines displayed by said 60 calendar sheet.

3. The combination of a casing having a sight opening, a calendar sheet having week date lines movable within said casing opposite said sight opening, means for moving 70 said calendar sheet, and transparent material partially covering such calendar sheet and slightly obscuring the same; such obscuration being discontinued at one point to expose any single week date line in clear 75 sight to the exclusion of the others.

4. The combination of a casing, rollers therein, a calendar sheet mounted on said rollers and carrying a plurality of numerals arranged in week date lines; said casing 80 having a sight opening, and a pair of transparent sheets carried by said casing in said sight opening through which a definite number of week date lines may be viewed; said sheets being spaced apart centrally of said 85 sight opening to disclose in clear view the dates or days of any single week displayed by said calendar sheet.

5. The combination of a casing, rollers therein, a calendar sheet mounted on said rollers and covering a plurality of week dates; said casing having a sight opening, and a pair of transparent sheets carried in said sight opening; said sheets being colored or shaded to partially obscure certain of the 90 dates and spaced apart to disclose the dates or days of any single week displayed by said 95 calendar sheet.

CARL B. COOK.
